US00D805591S

(12) **United States Design Patent** (10) **Patent No.:** **US D805,591 S**
(45) **Date of Patent:** **** Dec. 19, 2017**

(54) **BALL RETURN TRAINING DEVICE**

(71) Applicant: **PRO PERFORMANCE SPORTS, L.L.C.**, Carlsbad, CA (US)

(72) Inventors: **Monica Miller**, Encinitas, CA (US); **Richard Huth**, Encinitas, CA (US)

(73) Assignee: **PRO PERFORMANCE SPORTS, LLC**, Carlsbad, CA (US)

(**) Term: **15 Years**

(21) Appl. No.: **29/579,137**

(22) Filed: **Sep. 28, 2016**

(51) LOC (10) Cl. **21-02**

(52) U.S. Cl.

USPC **D21/705**; D21/698

(58) **Field of Classification Search**

USPC D21/302-306, 698-705, 780, 788, 790; 473/415-496, 172, 173, 197; 273/348, 273/394, 396, 397, 398, 400, 401, 402, 273/406, 407
CPC . A63B 63/00; A63B 63/004; A63B 2063/001; A63B 2063/002; A63B 2063/005; A63B 69/00; A63B 69/0002; A63B 69/0097; A63B 69/3623; A63B 2069/0006; A63B 2069/3626; A63B 2069/401; A63B 71/0036; A63B 71/022; A63B 2210/50; A63B 2210/52; A63B 2210/54; A63B 2225/09; A63B 2243/00; A63B 2243/0025
